UNITED STATES PATENT OFFICE.

HAKON K. OLSEN, OF COALVILLE, UTAH TERRITORY.

SAWING-MACHINE.

SPECIFICATION forming part of Letters Patent No. 275,069, dated April 3, 1883.

Application filed August 9, 1882. (No model.)

To all whom it may concern:

Be it known that I, HAKON K. OLSEN, of Coalville, in the county of Summit and Territory of Utah, have invented a new and Improved Sawing-Machine, of which the following is a full, clear, and exact description.

Reference is to be had to the accompanying drawings, forming a part of this specification, in which similar letters of reference indicate corresponding parts in both the figures.

Figure 1 is a perspective view of my improved sawing-machine. Fig. 2 is a detail view of the feeding apparatus.

The object of my invention is to furnish an easy-working and rapid-cutting machine for felling trees and sawing logs into lengths.

Referring to the drawings, A is a frame, having a slot lengthwise through its center, containing a feed-screw, B. The frame A is pivoted at *a* to the upright post C, and is capable of being turned either in a horizontal or vertical position by changing it on the pivot at *a*. On the screw B is placed a nut, B', to which a sleeve or guide, D, is rigidly attached at right angles with the screw B and the frame C. Passing through the sleeve D is a sliding bar, E, whose outer end is widened and slotted and provided with a spring-bolt, *b*, for entering the hole in the end of the saw F. The 30 inner end of the bar E is connected by a pivot-joint, *c*, to the connecting-rod G, whose outer end is provided with a suitable box connecting it with the bar *n* of the adjustable crank H, the ends of the bar *n* being secured in holes *o* in the crank-arms H, the shafts of which are journaled in the movable blocks *d d* in the slotted leaning posts I I. The crank-arms H are provided with holes *o* at different distances for shortening or lengthening the stroke of the 40 saw. At one end the shaft of the crank H is simply fitted to its box in the movable block *d*. At the opposite end it projects beyond the box, and is provided with a gear-wheel, *e*, to which the power is applied by a larger gear-wheel, *J*. The gear-wheel *J* is fixed on the shaft *f*, which is journaled in the upper part of the movable boxes *d d* in the slotted posts I I. Near the end the straight shaft *f* is provided with a cone-pulley, *g*, which is connected

with a like pulley, *g'*, on the end of the screw 50 B by the belt *i*.

K is a windlass journaled in the top of the leaning posts I I, and provided with ropes *j j*, fastened to the movable blocks *d d*, and running over pulleys *k k' k'*, for the purpose of 55 raising or lowering and holding all the parts supported by the movable blocks *d d*, and to accommodate the driving mechanism to the position of the saw. The windlass K is provided with arms K' for operating it, and the 60 arms are retained in position by a pin, *l*, which enters a hole in the standard I.

This machine is light and portable, and may be handled and operated by one or more men, or by steam or other power applied by belt or 65 universal-jointed rods.

The frame A can be fastened either in a vertical or horizontal position by the clamping-screws M. It also can be set to saw at any 70 angle.

When the saw is making a vertical or inclined cut, it is detached from the feed-screw and feeds downward by its own gravity.

Two saws can be used by making the screw B with a right-hand screw on one half and a 75 left-hand screw on the other half, so as to feed both saws inwardly toward the center of the tree.

Having thus described my invention, I claim as new and desire to secure by Letters Patent— 80

1. The combination, with the sliding saw-carrier E, of the sleeve D, the nut B', attached thereto, and the slotted frame A, pivoted to a post, C, at *a*, as and for the purpose specified.

2. The combination, with the sliding saw-carrier E, of the rod G, connected therewith by a pivot-joint, *c*, the bar *n*, connected with said rod by a box, the crank-arms H, having holes *o*, the movable blocks *d*, and the slotted posts I, the gear-wheel *e* on crank-shaft, and 90 the gear-wheel *J* on a shaft, *f*, connected with the screw B, whereby the saw may be reciprocated and fed, as described.

HAKON KERSHAW OLSEN.
